UNITED STATES PATENT OFFICE.

EMIL KREUSER, OF MECHERNICH, GERMANY.

ELECTROMAGNETIC ORE-SEPARATOR.

SPECIFICATION forming part of Letters Patent No. 638,128, dated November 28, 1899.

Original application filed February 28, 1899, Serial No. 707,212. Divided and this application filed May 12, 1899, Serial No. 716,607. (No model.)

To all whom it may concern:

Be it known that I, EMIL KREUSER, retired director of Royal Mines, a citizen of Germany, residing at Mechernich, Rhine Province, Germany, have invented certain new and useful Improvements in Electromagnetic Ore-Separators, of which the following is a specification.

This application is a division of my application filed February 28, 1899, Serial No. 707,212.

This invention relates to electromagnetic ore-separators consisting of two revolving cylindrical bar-electromagnets the cylindrical poles of different sign of which are placed opposite and in near proximity to each other, the space between such poles serving as the operative magnetic field through which the pulverized ore is made to pass. In such electromagnetic ore-separators it would often be advantageous for the separating process that the magnetic attraction should only be exercised by the poles of one of the cylinders. According to the present invention this is effected by covering the poles of the electromagnet which is not desired to attract the ore with a non-magnetizable material that revolves with the magnet, so that while such covering prevents the ore from adhering to the electromagnet by attraction the magnetic lines of force still flow uninterruptedly from the poles of the one electromagnet to those of the other, so as to insure the necessary strong magnetic field for acting upon the ore. It is necessary that the thickness of the said covering should be at least one-half the space between the two rolls in order to have the desired effect. Such a covering of non-magnetizable material possesses the advantages that the ore to be treated can be delivered directly onto it without the use of conveying-belts such as have heretofore been used and which are subject to more or less rapid wear; also, that the ore can be led directly in close proximity to the magnetic poles at points where the intensity of attraction is greatest; also, that the air resistance can be reduced to a minimum and is not increased in proportion to the thickness of the conveying-belts, as with existing arrangements, so that powerfully-concentrated magnetic fields can be

produced, resulting in a correspondingly-great economy in the expenditure of electrical energy.

On the accompanying drawings is shown, by way of example, one arrangement of my above-described invention.

Figure 1 shows a cross-section of a pair of cylindrical electromagnets in which the one magnet has its cylindrical poles covered with non-magnetizable material. Fig. 2 shows a partial longitudinal section of the magnet with non-magnetizable covering; and Fig. 3 is a longitudinal sectional view of one of the electromagnets, showing suitable means by which it may be magnetized.

A and A' are two oppositely-revolving cylindrical polar surfaces of the electromagnets, the polar surface A' being provided with a closely-fitting covering of non-magnetizable material *a*. The ore is delivered directly onto the covered magnet A', as shown, so that it serves as a conveying-roller. It does not cooperate in the actual separation of the ore, but only serves for strengthening the magnetic field by the induction of lines of force. Owing to the thickness of the covering *a* the ore is brought to a corresponding extent nearer to the polar surface of the operative magnet A, whereby the useful effect is increased and the magnetic field is utilized to greater advantage. This covering of the pole is applicable to all types of ore-separators in which only two circular poles rotate in opposite directions. It is particularly suitable for two-bar roller-magnets rotating in opposite directions, and is also of advantage in other constructions—for instance, those of United States Patent, No. 264,620, dated September 19, 1882. The mode of exciting the rotating magnet-poles is immaterial for the purpose of this invention. The coils may be mounted on fixed magnet-cores and the pole-pieces alone revolve, or the coils may be wound on the cores and may rotate with them, as shown in Fig. 3, where A is a magnet-core, with its covering *a*, and B the coils connected with a contact-wheel *r*.

Having thus described the nature of this invention and the best means I know of carrying the same into practical effect, I claim—

In electromagnetic ore-separators consisting of a pair of oppositely-revolving cylindrical electromagnets, the combination with the polar surfaces of the one electromagnet 5 of a closely-fitting covering of non-magnetizable material, whereby the poles of this magnet are prevented from attracting the ore, while at the same time they coöperate in producing the necessary flux of magnetic lines 10 of force, and also serve to convey the ore to

and from the magnetic field, substantially as described.

In testimony whereof I have hereunto set my hand in presence of two subscribing witnesses.

EMIL KREUSER.
